UNITED STATES PATENT OFFICE.

HUGH M. ROCKWELL, OF BRISTOL, CONNECTICUT, ASSIGNEE, BY MESNE ASSIGNMENTS, TO STANDARD STEEL AND BEARINGS INCORPORATED, OF WILMINGTON, DELAWARE, A CORPORATION OF DELAWARE.

CONTINUOUS READING GAUGE.

Application filed June 7, 1920. Serial No. 387,180.

To all whom it may concern:

Be it known that I, HUGH M. ROCKWELL, a citizen of the United States, and a resident of Bristol, in the county of Hartford and 5 State of Connecticut, have invented certain new and useful Improvements in Continuous Reading Gauges, of which the following is a specification.

My invention relates to measuring instruments, and more particularly to devices for 10 indicating the dimensions of an article during the period in which the article is being operated upon by a reducing tool. Such a device is of particular utility during the operation of grinding the race members of an anti-friction bearing.

Certain articles of manufacture, such, for example, as anti-friction bearings, depend upon the accuracy of their manufacture for 20 their efficiency and durability. The race members of anti-friction bearings cannot vary over five-thousandths of an inch from a given standard and satisfactorily serve the purpose for which they are intended. To 25 obtain the necessary exactness of manufacture, careful grinding of the race members is imperative. To determine when the dimensions of the races were correct, it has heretofore been customary to stop operation

30 upon the work and apply thereto a suitable measuring instrument, after which the work was removed or operations thereon resumed according to the condition of the work. This method of gauging did not produce 35 uniform pieces of work, there being quite a percentage of waste due to excessive grinding, and contributed quite materially to the labor cost of the bearing, due to the time consumed in the gauging of the work.

40 It is the object of my invention to provide a gauge, a contact member of which will engage the surface operated upon during the period of operation upon the work, and by means of which it may be determined when 45 the work being operated upon has attained the desired dimension.

A further object of this invention is to provide a device of this character which is simple in construction and efficient in its operation.

To accomplish the objects of this invention, I provide two or more contact members, preferably diamond chips, on arms or the like, so arranged that the contact mem-

bers may be swung into or out of engagement with the work while it is being operated upon. One of the contact-carrying arms is pivotally mounted upon a standard in such a way that when the contact engages the work, the axis of the arm is substantially parallel to the axis of rotation of the work, the standard itself, being mounted, preferably on the machine in which the work is being operated upon, for rotation about an axis also substantially parallel to the axis of rotation of the work but spaced from the axes of rotation both of the work and the contact-carrying arm. A second contact-carrying arm is pivotally mounted on the first contact-carrying arm and is arranged with its axis parallel to the axis of the first arm. Resilient means are provided to keep the contacts in engagement with the work. An indicator mounted on the first arm is arranged to be operated by the second arm to indicate the condition of the work being reduced.

Other objects of the invention will be apparent from a reading of the following specification and the appended claims.

Referring now to the drawings, wherein is disclosed an embodiment of the invention,

Fig. 1 is a side elevation;

Fig. 2 is an end elevation.

For the purpose of illustrating the use and operation of one embodiment of the gauge, I have disclosed it as utilized to measure the diameter of a ball groove in the inner race member of a ball bearing. It is not limited to such use but may be utilized wherever it is desirable to gauge or measure work while being operated upon.

In Fig. 1, 1 is the work being reduced to size, and 2 is the reducing tool or grinding wheel. A post or other support 3 is attached to the machine or otherwise maintained in proper position. Rotatably mounted on the post 3 with its axis of rotation parallel to the axis of the work and held against movement axially thereof by the set screw 4, is the standard 5 comprising an arcuate body portion, the outer end 6 of which is parallel to the post 3. A yoke 7 is carried by the end 6 of the standard, and between the legs 8 of the yoke is pivotally or rotatably mounted one end of the primary arm 9, in the free end of which is

located a contact 10. A pin 11 extends from the primary arm 9 on which is adjustably mounted a bracket 12, one portion of which is provided with the spaced lugs 13. The 5 secondary arm 14 is journalled on a shaft supported by the lugs 13. One end of the secondary arm engages a contact 15 while the other end engages the plunger 16 of the indicator 17 carried by the bracket 12. A 10 spring 18 carried by the member 19 on the bracket 12 holds the secondary arm in contact with the plunger and also serves to force the contact 15 toward the contact 10. The primary arm 9 is resiliently held with 15 the contact 10 in position to engage the work by means of the spring 20 connected at one end to the yoke 7 and at the other end to the pin 21 carried by the bracket 12. A spring-pressed plunger 22 carried by the 20 standard 5 and adapted to seat in either of the sockets 23 in the post 3 maintains the standard in or out of operative position.

To utilize this gauge, the standard 5 is swung into the position shown in Fig. 1. 25 As the standard approaches this position the contacts 10 and 15 engage the surface of the work and are forced apart. The spring 18 forces the contact 15 into engagement therewith. As the work is reduced by the 30 tool 2, the contacts approach each other and the distance between the contacts is indicated on the dial of the indicator 17. The reducing operation is continued until the desired condition of the work has been obtained, after which the standard 5 is swung 35 about the post 3 to remove the contacts from the work. The latter is removed from the spindle and a new piece of work placed.

It is, of course, understood that the particular device shown and described in the 40 present application illustrates merely a preferred form of construction and arrangement of parts, which, it has been found, will successfully carry out the principles of my invention, and various changes and modifications of details may be easily made 45 without departing from the spirit of my invention as defined in the appended claims.

What I claim is:

50 1. In a device of the character indicated, a support, a standard rotatably mounted thereon, a primary arm pivotally mounted on said standard, a secondary arm rotatably supported by the primary arm, contact members on each arm adapted to engage a piece of work, and resilient means to force said contact members against the work.

55 2. In a device of the character indicated, a support, a standard rotatably mounted thereon, a primary arm pivotally mounted on said standard, a bracket carried by said primary arm, a secondary arm rotatably mounted on said bracket, contact members 60 on each arm adapted to engage a piece of

work, and resilient means to force said contact members against said work.

3. In a device of the character indicated, a support, a standard rotatably mounted thereon, a primary arm pivotally mounted on said standard, a bracket carried by said primary arm, a secondary arm rotatably mounted on said bracket, contact members on each arm adapted to engage a piece of work, and resilient members connecting said bracket and secondary arm, and said bracket and primary arm whereby said contact members are forced against the work. 75

4. In a device of the character indicated, a support, a standard rotatably mounted thereon, a primary arm pivotally mounted on said standard, a secondary arm rotatably supported by the primary arm, contact members on each arm adapted to engage a piece of work, resilient means to force said contact members against the work and means to lock said standard relative to said support. 80

5. In a device of the character indicated, a support, a standard rotatably mounted thereon, a primary arm pivotally mounted on said standard, a bracket carried by said primary arm, a secondary arm rotatably mounted on said bracket, contact members on each arm adapted to engage a piece of work, resilient means to force said contact members against said work, and means to lock said standard relative to said support. 90

6. In a device of the character indicated, a support, a standard rotatably mounted thereon, a primary arm pivotally mounted on said standard, a bracket adjustably carried by said primary arm, a secondary arm rotatably mounted on said bracket, contact members on each arm adapted to engage a piece of work, resilient members connecting said bracket and secondary arm, and said bracket and primary arm whereby said contact members are forced against the work, and means to lock said standard relative to said support. 100

7. In a device of the character described, a primary arm, a secondary arm pivotally supported thereby, contact members on each of said arms adapted to engage a piece of work, means to force said contact members against the work, an indicator supported by said primary arm, and operatively associated with said secondary arm. 105

8. In a device of the character indicated, a standard, a primary arm pivotally mounted thereon, a secondary arm pivotally supported by said primary arm, contact members on each of said arms adapted to engage a piece of work, means to force said contact members against the work, an indicator supported by said primary arm and operatively associated with said secondary arm. 110

9. In a device of the character indicated, 115

a support, a standard movably mounted on said support, a primary arm pivotally mounted thereon, a secondary arm pivotally supported by said primary arm, contact members on each of said arms adapted to engage a piece of work, means to force said contact members against the work, an indicator supported by said primary arm and operatively associated with said secondary arm.

10. In a device of the character indicated, a support, a standard movably mounted on said support, a primary arm pivotally mounted on said standard, a bracket mounted on the primary arm, a secondary arm pivoted to said bracket, contact members on each of said arms adapted to engage a piece of work, means to force said contact members against the work, an indicator supported by said primary arm and operatively associated with said secondary arm.

11. In a device of the character indicated, a support, a standard movably mounted on said support, a primary arm pivotally mounted thereon, a secondary arm pivotally supported by said primary arm, contact members on each of said arms adapted to engage a piece of work, means to force said contact members against the work, an indicator supported by said primary arm and operatively associated with said secondary arm.

arm, and means to lock said standard relative to said support.

12. In a device of the character described, a standard, a primary arm pivotally mounted thereon, a bracket mounted on said primary arm, a secondary arm pivotally mounted on said bracket, contact members on each of said arms adapted to engage a piece of work, an indicator supported by said primary arm and operatively associated with said secondary arm, and resilient members connecting said bracket and secondary arm and said bracket and primary arm whereby said contact members are forced against the work.

13. In a device of the character described, a support, a standard movably mounted on said support, a primary arm pivotally mounted thereon, a bracket mounted on said primary arm, a secondary arm pivotally mounted on said bracket, contact members on each of said arms adapted to engage a piece of work, an indicator supported by said primary arm and operatively associated with said secondary arm, and resilient members connecting said bracket and secondary arm and said bracket and primary arm whereby said contact members are forced against the work.

HUGH M. ROCKWELL.
